[57] CLAIM

The ornamental design for a combined bottle and stand, as shown described.

DESCRIPTION

FIG. 1 is a front elevational view of the combined bottle and stand showing my new design;

FIG. 2 is a rear elevation view thereof;

FIG. 3 is a right side view thereof, the opposite side being a mirror image thereof;

FIG. 4 is a top plan view thereof;

FIG. 5 is a bottom plan view thereof;

FIG. 6 is a top perspective view thereof;

FIG. 7 is a front elevation view of the box removed from the stand, the rear view being a duplicate thereof;

FIG. 8 is a right side view thereof, the left side view being a duplicate thereof;

FIG. 9 is a top plan view thereof;

FIG. 10 is a bottom plan view thereof; and,

FIG. 11 is a top perspective view thereof.
